Attorney

UNITED STATES PATENT OFFICE.

JOHN HUDSON, OF DETROIT, MICHIGAN.

HAME-FASTENER.

SPECIFICATION forming part of Letters Patent No. 271,247, dated January 30, 1883.

Application filed October 17, 1882. (No model.)

To all whom it may concern:

Be it known that I, JOHN HUDSON, of Detroit, county of Wayne, State of Michigan, have invented a new and useful Improvement 5 in Hame-Fasteners; and I declare the following to be a full, clear, and exact description of the same, such as will enable others skilled in the art to which it pertains to make and use it, reference being had to the accompanying 10 drawings, which form a part of this specification.

My invention consists of the contrivances and combinations of the parts hereinafter specified, and more particularly pointed out in the 15 claims.

In the drawings, Figure 1 represents a plan view, and Fig. 2 a side elevation, of a hame-fastener embodying my invention. Fig. 3 represents the same with a strap in position and 20 a buckle secured in place by the strap. Fig. 4 is a variation in which the loop for the end of the strap is dispensed with and the device adapted for use upon the end of a strap.

It is the object of this invention to make a 25 hame-fastener which shall hold one end of the hame-strap and retain an ordinary buckle for the other end of the strap, and which shall at the same time form a secure fastening for the loop of one of the hames and shorten the length of 30 the strap, and all without the use of rivets and without the necessity of sewing.

In carrying out my invention, A represents the side bars of my hame-fastener.

B is a hook formed at one end to engage 35 with one of the hame-loops. C is a cross-bar at the opposite end. C' is another cross bar, preferably recessed for the tongue of the buckle at c', and at c² provided with a teat for engaging a hole in the strap. C² is an ele- 40 vated cross-bar, which lifts the strap at this point so as to make it engage snugly with the teat c², and also to insure a secure fastening of the hame-loop in the hook B. C³ is another cross-bar, which serves the place of a front 45 loop for the free end of the strap D.

E is a buckle of the ordinary kind.

The operation of the device is apparent from the drawings. The loop F, which is attached to one of the hames, is engaged with the hook 50 B. The end d of the strap is then turned in, as shown, thus keying the device securely against

displacement from the hame-loop. The free end of the strap is then in condition to engage the loop at the extremity of the other hame in the usual manner, after which it is drawn up 55 through the buckle E and its end passed through the front loop, C³.

It will be observed that the buckle is held in place solely by the strap.

I have described this device as a hame-fastener. It is apparent, however, that it is equally well adapted in many other locations upon a harness or in other apparatus. I would therefore have it understood that I do not limit myself in its employment to hames, though it is 60 well adapted for that purpose. So, also, the feature of locking or keying the device to a ring or loop by hooking the loop into the hook and then turning in the end of the strap is important, whether the front cross-bar is or is 65 not employed, and with or without the buckle—as, for instance, in the device shown in Fig. 4 both the front loop and the buckle are dispensed with—the device being adapted for connection with the end of a strap, and may be 70 employed, for instance, in fastening a hitching-strap to the bit-ring, or may be used instead of a snap in securing the holdback to the breeching-ring.

What I therefore claim is—

1. A fastener for hames and other articles, composed of the side bars, A, having at the front end the hook B and cross-bar C³, forming a front loop, a cross-bar, C', between the hook and rear bar, provided with a stationary projecting teat, c²; to engage a hole in a strap, and an elevated cross-bar, C², in front of the teat for lifting the strap and insuring its engagement with the teat, substantially as described. 85

2. A fastener for hames and other articles, 90 consisting of the side bars, A, having the front loop, C³, and hook B, the cross-bar C' at the rear end, the cross-bar C', provided with the stationary projecting teat c² and recess c', and the elevated cross-bar C², arranged in front of 95 the said teat, substantially as described.

In testimony whereof I sign this specification in the presence of two witnesses.

JOHN HUDSON.
